MANIFOLDING RECORD ASSEMBLY

Edward Kirby Bottle, Elmira, N. Y., assignor, by
mesne assignments, to American Sales Book
Company, Inc., a corporation of Delaware

Application June 3, 1930, Serial No. 459,044

12 Claims. (Cl. 282—12)

This invention relates to improvements in record receiving devices, ordinarily including long continuous record and transfer strips interleaved in manifolding transfer relation with each other, or single manifolding sets of record and transfer leaves, and adapted to receive record inscriptions applied in any well known manner, but particularly adapted for receiving inscriptions made in various recording apparatus such as auto-graphic registers, typewriters, teletypewriters, billing and accounting machines, and the like.

It is a fact that considerable difficulty has been experienced in connection with record receiving devices or manifolding assemblies and particularly where the latter are utilized in conjunction with machines and apparatus of the type mentioned. More particularly, this difficulty is attributable to the tendency of the several strips or leaves of a record pile or assembly to creep out of alignment as they move towards and through the machine. The results of the several sheets of a record set moving out of alignment with respect to each other are apparent and with this in mind, it has been proposed that the record strips be periodically attached to each other to prevent any danger of appreciable relative movement and this attachment has usually been placed at one point in each leaf set. However, with this attachment provided for and the danger of creepage eliminated, other difficulties have arisen in separating the record and carbon leaves in the actual practical commercial use of the manifolding assembly.

The present invention aims to provide a construction by means of which it will be practicable to attach the sheets or leaves of each manifolding pile or set to each other (to prevent relative movement thereof), and also to embrace in such an attachment a construction whereby a ready subsequent separation of the sheets or leaves of the set may be effected.

A further object of the invention is that of achieving the foregoing object without danger of destroying or mutilating the inscription receiving sheets and in which the separation into separate piles or groups of the inscribed record sheets and transfer leaves may be effected with minimum effort and time and by a relatively inexperienced operator.

A further object is that of furnishing a record of this nature embodying a relatively simple construction, capable of manufacture by automatic machinery so that production costs may be lowered.

With these and further objects in mind, reference is had to the attached sheet of drawings, illustrating preferred practical embodiments of the invention, and in which:

Fig. 1 is a perspective view of a record pile or set which forms one part of the long continuous manifolding assembly and has been severed therefrom;

Fig. 2 is a similar view of a fan-fold type record; and

Fig. 3 is a diagrammatic side elevation of a long continuous manifolding assembly transversely folded at intervals in a zig-zag supply pack.

In these illustrations, the record of Fig. 1 has been shown to embody a construction suitable for use in a teletype apparatus or other machine of the pin feed type, and the construction of Fig. 2 has been illustrated as embodying no feed perforations.

It will be understood that the latter record might embody these feed perforations and that they might be eliminated from the record of Fig. 1. In other words, it is customary to provide feed perforations in one or more of the assembly strips with which one or more toothed wheels of the apparatus cooperates. This is in many respects desirable, but it will be understood that in certain aspects an unperforated record will cooperate properly with a teletype apparatus, and a perforated record will likewise cooperate to advantage with many other forms of inscribing machines.

Referring particularly to Fig. 3, a record assembly of the long continuous traveler type is shown as being folded transversely at longitudinally spaced intervals therealong into a zig-zag folded supply pack wherein the successive stacks or sets of relatively superposed record and transfer sheets are positioned between the adjacent fold lines of the assembly. The complete record assembly thus includes long continuous traveler record strips and one or more long continuous traveler transfer or copying strips all interleaved with each other in manifolding transfer relation and all having transverse weakened severance lines such as the lines indicated at 6 which may be provided by lines of perforations and are indicated by the serrated edges of the several record and transfer sheets. These transverse weakened severance lines 6 are longitudinally spaced apart at form-length or sheet-length intervals in both the record and transfer strips so as to define the sets or stacks of relatively superposed record and transfer sheets. These sheets are

positioned in succession in end to end relation to form the long continuous record and transfer strips. The sets of record and transfer sheets may be successively severed from the assembly 5 along the weakened severance lines. As mentioned, the assembly is preferably folded zig-zag into a compact supply pack and it is preferable to fold the assembly along the respective sets of weakened lines, but it will be understood that 10 the assembly of record and transfer strips may be otherwise arranged as desired for convenient use, or for handling, etc.

As shown in Fig. 1, the assembly includes an upper record sheet 7 and a lower record sheet 8 15 each of which may have upon its upper face a printed form. These sheets are formed with feed apertures or perforations 9 and interposed between them is a sheet or leaf 10 of copying material such as carbon paper. As shown in Fig. 1, 20 it is preferred to make the transfer strip or sheet 10 narrower than the record layers, so that the feed apertures 9 lie outwardly beyond the edges of the transfer strips at both assembly edges. It will be understood that for the sake of simplicity 25 of illustration, merely the minimum number of layers or strips have been shown, i. e. upper and lower inscription receiving sheets and a single interleaved copying layer. Obviously any desired number of layers might be provided.

With a view to securing the individual layers 30 of the manifolding assembly against relative movement, any desirable securing means may be employed. In the embodiment under consideration a staple 11 is utilized for this purpose, and 35 the length of this staple is shown exaggerated for the purpose of clarity. This fastening means which, of course, might be of any desirable nature such as stitching, a rivet, pasting, etc., serves to secure the sheets or strips of the manifolding 40 assembly in the manner desired, and the difficulty heretofore noted is experienced after a form length or set of leaves has been severed from the record assembly and the individual leaves or sheets of the severed set are to be segregated.

With this in mind, the staple passes through the 45 carbon leaf 10 as well as the record leaves or sheets 7 and 8, and the latter are provided with supplemental lines of perforations 12, having their ends preferably somewhat spaced from the adjacent serrated edge or severance line 6, but as 50 a consequence of which areas of the inscription receiving sheets may readily be removed from the bodies of the latter and the fastening means 11 being disposed within these areas.

It is preferred to position the supplemental 55 weakened lines 12 intermediate the longitudinal edges of the assembly as shown so that the severable finger-grip areas defined by these lines will be spaced inwardly from both longitudinal 60 assembly edges and thus protected from damage. In the embodiment shown, each severance line 12 has its opposite ends transversely spaced apart and terminating in the vicinity of the respective 65 weakened transverse severance lines 6, but preferably spaced slightly from the latter as above mentioned. The transfer element or elements 70 10 are preferably, as shown, unprovided with supplemental weakened severance lines corresponding to the severance lines 12 of the record elements. The edge of each transfer leaf 10 which is opposite to the fastening device 11 of each set of record and transfer leaves, is provided with a notch or marginally offset portion 13 so as to provide a grip escaping aperture or selective grip formation. These notches or apertures 13 may

be variously positioned but are spaced from the respective fastenings 11 and provide relatively offset marginal portions of the record and transfer sheets of a severed set thus making a selective grip formation on each severed set where-by the record sheets or leaves may be selectively gripped to the exclusion of the transfer leaf or leaves. 5

In use, the record as in Fig. 3 is fed through and suitably beyond the inscribing station of any 10 desired type of apparatus. At the inscribing station, the sheet 7 has inscribed upon it the desired indicia which, by means of the copying leaf 10—or otherwise—is transferred to the upper face of the sheet 8, this duplication occurring 15 according to the number of layers in the record pack. Thereafter, the record is severed with or without the assistance of a tearing bar to segregate the inscribed pack or set of leaves from the body of the record assembly. The severed set 20 may be individually filed and may receive further inscriptions. When it is desired to separate the record and transfer sheets of the severed set, the operator merely grasps the severable finger grip areas defined by the weakened lines 12, and also 25 grasps the inscription receiving sheet in line with the openings or cut-away portions 13, whereupon a pull exerted in opposite directions, serves to remove said finger grip areas together with the fastening devices from the record sheets. When 30 this occurs, it will be obvious that the transfer leaf or leaves 10 will be removed from interleaved relation with the record sheets. It will be understood that single manifolding sets such as shown in Figs. 1 and 2 may be made and used independently of the long continuous assembly as 35 shown in Fig. 3, or they may be successively severed from said assembly along the weakened severance lines 6. Thus, by one operation it becomes feasible not alone to eliminate the fastening element, but also to segregate the copy or other desired leaves of the pack from the remaining sheets thereof. 40

Referring to Fig. 2, it will be noted that in lieu of separate zigzag superposed strips of inscription receiving and copy materials, a fan-fold construction is shown including a relatively broad web 14 folded longitudinally of its length to provide the fan-fold construction in addition to preferably being folded transversely and provided adjacent these lines of fold with lines of severance. The longitudinal folds of the wide web 14 are positioned at the opposite longitudinal edges of the manifolding assembly and function to attach together the record strips which are 45 adjacent to one another. Thus, it will be seen upon reference to Fig. 2, that the top and next underlying record strips are attached by the longitudinal fold shown at the left near the top of Fig. 2, while the second and third record 50 leaves or strips from the top are similarly attached by the fold at the right in Fig. 2. Interleaved between the record strips or layers of the web 14 are strips of copying material 15 which as at 16 may have their corner portions obliquely disposed. The record and transfer strips are also formed with transverse weakened severance lines corresponding to the line 6 of Fig. 1 and positioned in line with the corresponding fold lines of the inscription receiving material. 55

In order to retain the strips of copying material against displacement, a staple 17 or other fastening expedient is resorted to and similarly to the construction shown in Fig. 1, a supplementary line of perforations 18 is formed in each 70 75

layer of the web 14 and serves to isolate that portion of the same which mounts the fastening element.

Consequently with the record assembly inscribed and the pack as shown in Fig. 2 removed therefrom by tearing along the transverse lines of perforations, an operator by simply grasping the finger grip areas within the rows of perforations 18 and at the same time grasping the record strips of the web 14 in line with the selective grip formation formed by the removed corner portions 16, and exerting a pull in opposite directions, can very quickly and easily sever the finger grip areas carrying the fastening element or other means and thus segregate the strips of copying material from the inscribed record sheets.

It will be understood that by having the perforations 12 or 18 begin at a point not immediately adjacent to the line of severance, the danger of the tear line following these perforations is reduced to a minimum.

Thus, among others, the several objects of the invention as specifically described may be achieved. It will be understood, moreover, that numerous changes in construction and rearrangement of the parts might be resorted to without departing from the spirit of the invention as defined by the claims.

Having described my invention, what I claim as new and desire to secure by Letters Patent, is:

1. A record assembly including a plurality of consecutive record packs, severable from each other, along predetermined lines of severance, fastening means common to all of the sheets of each of said packs, certain of said sheets being formed with lines of scoring each having its ends terminating adjacent to but short of said lines of severance, and said fastening means being disposed within the spaces defined by said lines of scoring and said lines of severance.

2. A record assembly including a plurality of inscription receiving sheets formed with rows of feed perforations, an unperforated copying sheet between said first named sheets, fastening means common to all of said sheets, at least one sheet of one type being formed with a line of severance defining an area within which said fastening means is disposed and another sheet being formed with a grip escaping aperture to one side of said area.

3. Superposed record strips divided at given intervals by straight transverse weakening lines to form successive sets of superposed record sheets, and a transfer strip between adjacent record strips transversely divided by weakened portions at similar intervals to provide a transfer sheet between adjacent record sheets, the record sheets of each set having registered relatively short weakening lines each intercepting a transverse line at two points to provide a detachable binding section, and a staple securing said sheets and the interposed transfer sheet together at the binding section, said transfer sheet at its opposite margin being formed with an edge portion inwardly offset from the adjacent transverse line of the record strips.

4. Superposed record strips divided at intervals by weakening lines to form successive sets of superposed record sheets, and a transfer strip between adjacent record strips transversely divided by weakened portions at similar intervals to provide a transfer sheet between adjacent record sheets, the record sheets of each set having registered relatively short weakening lines each intercepting a transverse line to provide a detach-

able binding section, and a staple securing said sheets and the interposed transfer sheet together at the binding section, each of said short weakening lines lying adjacent to one of said staples and having its opposite end portions positioned adjacent to the corresponding said record strip weakening line intermediate the ends of the latter, said transfer sheet at its opposite margin being formed with an edge portion offset from the adjacent transverse line of the record strips.

5. Superposed record strips and interleaved transfer strips divided at intervals by registered transverse weakening lines to form sets of interleaved record and transfer sheets, selected ones only of said sheets having at one edge of the set of sheets finger-grip areas extending inwardly from said edge of the set of sheets and defined by lines of severance including a weakened severing line while the remaining sheet or sheets of the set are free of such lines of severance at corresponding parts thereof, and fastening means located in said finger-grip areas for securing the sheets of the set together, said sheets containing said weakened finger-grip areas having offset therefrom marginal portions projecting beyond the contiguous marginal portions of the sheets which are free of the severance lines of the weakened finger-grip areas.

6. A unitary manifolding assembly including, in combination, a unitary free set of record sheets, having a binding in which said sheets are bound, and at least one transfer sheet bound in said binding positioned in overlapping manifolding relation with said record sheets, selected ones only of said sheets having finger-grip areas extending inwardly from the bound edge of said set of sheets, of less width than said bound edge, and defined by lines of severance including weakened severing lines, the remaining sheet or sheets being free of such lines of severance at corresponding parts thereof and the sheets of the set being bound within said finger-grip areas.

7. A record assembly including, in combination, a plurality of inscription receiving sheets, a copying sheet positioned in transfer relation between said inscription receiving sheets, at least one of said sheets but less than the whole number having rows of feed apertures positioned at opposite longitudinal marginal edge portions therec, while the remaining sheet or sheets is narrower than the others and has its longitudinal edges lying within those of the others and is unprovided with feed apertures corresponding to those mentioned, fastening means common to all of said sheets and binding the latter together, one or more of said sheets, but less than the whole number, each being formed with a line of severance positioned to provide a detachable area within which said fastening means is interposed, and another sheet having a marginal portion spaced from said detachable area and offset from the adjacent marginal portions of the adjacent sheet or sheets so as to provide a selective grip formation.

8. A unitary manifolding assembly including, in combination, a set of record sheets having a binding in which said sheets are bound, and at least one transfer sheet bound in said binding positioned in overlapping manifolding relation with said record sheets, selected ones only of said sheets having finger-grip areas extending inwardly from the bound edge of said set of sheets, of less width than said bound edge, and defined by lines of severance including weakened severing lines, the remaining sheet or sheets being

- free of such lines of severance at corresponding parts thereof and the sheets of the set being bound within said finger-grip areas, one or more of said sheets but less than the whole number
- 5 having rows of feed perforations positioned at opposite longitudinal marginal edge portions thereof while the remaining sheet or sheets is narrower than the others and unprovided with feed apertures corresponding to those mentioned.
- 10 9. A unitary manifolding assembly including, in combination, a set of record sheets, having a binding in which said sheets are bound, and at least one transfer sheet bound in said binding positioned in overlapping manifolding relation
- 15 with said record sheets, selected ones only of said sheets having finger-grip areas extending inwardly from the bound edge of said set of sheets, of less width than said bound edge, and defined by lines of severance including weakened sever-
- 20 ing lines, the remaining sheet or sheets being free of such lines of severance at corresponding parts thereof and the sheets of the set being bound within said finger-grip areas, said record sheets which are next to each other being attached to-
- 25 gether by a fold at a longitudinal edge of the assembly.
10. A manifolding assembly including, in combination, superposed record and transfer strips interleaved with each other, said record and
- 30 transfer strips being divided at intervals by transverse weakening lines to form sets of interleaved record and transfer sheets, selected ones only of said sheets having at one edge of the set finger-grip areas extending inwardly from said edge and
- 35 defined by lines of severance including a weakened severance line, while the remaining sheet or sheets of the set are free of such lines of severance at corresponding parts thereof, said lines of severance each having the opposite ends
- 40 thereof spaced apart and terminating in the vicinity of the respective said transverse weakening lines and being positioned intermediate the longitudinal assembly edges so as to form the said finger-grip areas of less width than that of the assembly, and fastening means located in said finger-grip areas for securing the sets together, said sheets with the weakened finger-grip areas having at parts offset from said areas marginal portions projecting beyond the adjacent marginal
- 45 portions of the sheets which are free of the said weakened severing lines of the weakened finger-grip areas.

11. A manifolding assembly including, in combination, superposed record and transfer strips interleaved with each other, said record and transfer strips being divided at intervals by transverse weakening lines to form sets of interleaved record and transfer sheets, selected ones only of said sheets having at one edge of the set finger-grip areas extending inwardly from said edge and defined by lines of severance including a weakened severance line, while the remaining 10 sheet or sheets of the set are free of such lines of severance at corresponding parts thereof, said lines of severance each having the opposite ends thereof spaced apart and terminating in the vicinity of the respective said transverse weakening lines and being positioned intermediate the longitudinal assembly edges so as to form the said finger-grip areas of less width than that of the assembly, and fastening means located in said finger-grip areas for securing the sets together, said sheets with the weakened finger-grip areas having at parts offset from said 15 marginal portions projecting beyond the adjacent marginal portions of the sheets which are free of the said weakened severing lines of the weakened 20 finger-grip areas, said record strips which are next to each other being attached together by a longitudinal fold extending along a longitudinal edge of the assembly.

12. A unitary manifolding assembly including, 30 in combination, a unitary free set of record sheets, having a binding in which said sheets are bound, and at least one transfer sheet bound in said binding positioned in overlapping manifolding relation with said record sheets, selected 35 ones only of said sheets having finger-grip areas extending inwardly from the bound edge of said set of sheets, of less width than said bound edge, and defined by lines of severance including weakened severing lines, said severing lines being positioned adjacent to said bound edge and having opposite end portions thereof positioned intermediate the extremities of said bound edge, the remaining sheet or sheets of the set being bound within said finger-grip areas, and marginal portions of the record and transfer sheets being relatively off-set at a part of the assembly remote 40 from said binding to provide a selective grip formation.

EDWARD KIRBY BOTTLE. 50
